CLAIM

The ornamental design for a door handle or replica thereof, as shown and described.

DESCRIPTION

FIG. 1 is an isometric view of a door handle or replica thereof in accordance with the present design;

FIG. 2 is a front elevation view thereof;

FIG. 3 is a rear elevation view thereof;

FIG. 4 is a top plan view thereof;

FIG. 5 is a bottom plan view thereof;

FIG. 6 is a right side elevation view thereof; and,

FIG. 7 is a left side elevation view thereof.
